UNITED STATES PATENT OFFICE.

EDWIN L. DUNHAM, OF QUINCY, MICHIGAN.

FARM-FENCE.

SPECIFICATION forming part of Letters Patent No. 268,466, dated December 5, 1882.

Application filed September 9, 1882. (No model.)

To all whom it may concern:

Be it known that I, EDWIN L. DUNHAM, of Quincy, in the county of Branch and State of Michigan, have invented certain new and useful Improvements in Farm-Fences; and I do hereby declare that the following is a full, clear, and exact description thereof, reference being had to the accompanying drawings, and to the letters of reference marked thereon, which form part of this specification.

This invention relates to a clamp for holding the ends of fence-rails in place.

The objects of my improvement are to hold the ends of the rails of a fence in place without nailing or bolting the rails, so that the fence can be readily put up and taken down; also, to provide an improved construction of parts in a device for clamping and holding in place the rails of a fence, as hereinafter fully described, and illustrated in the annexed drawings, in which—

Figure 1 is an end elevation, showing the parts B B in a clamping position. Fig. 2 shows the parts B B opened. Fig. 3 is a perspective view of two sections of a fence having my improved clamps applied to the panels for holding them in position.

My fence-clamp is composed of two sections pivoted together and adapted to receive the ends of the fence-rails between them. Each section comprises a horizontal base or sill, A, a vertical post, B, and an inclined brace, C, running from the base up to the upper portion of the post. The posts are secured to the sills at points near the inner ends of the latter, and these said sills or base portions of the two sections are pivoted together by means of a bolt, D, passing through the end of one sill and through the post and remaining sill at the point where said sill and post are secured together. In this way the inner ends of the sills lap or pass each other, as indicated, and for the purpose hereinafter described. Each inclined brace C is notched or halved at its lower end and fitted to a sill, the shoulder formed by said notch being received in a seat formed in the top of the sill. The upper end of the brace is similarly halved or notched, the shoulder formed by said notch being fitted in a notch formed in the post, near the upper end of the latter. The seats in the sills for the shoulders of the notched lower ends of the braces are indicated at C', while the notches

in the posts for the shoulders at the upper ends of the braces are indicated at C². These 55 braces are secured to the posts and sills by nails E, which prevent lateral displacement of the braces. The outer ends of the sills rest upon boards, blocks, or analogous supports, F, which serve to raise the sills above the ground, 60 and thereby allow the inner ends of the sills to be lowered, which movement on the part of the sills tends to bring the posts together, after the manner of a pair of jaws.

In putting up the fence the meeting ends of 65 the rails of the sections of fencing can be simply laid, one upon another, between the posts, the lower rail resting upon the inner ends of the sills between the posts.

It will be evident that the weight of the 70 rails will depress the inner ends of the sills, thereby causing the posts to clamp and hold the rails, and the greater the number of rails the more effective will be the clamping-power of the posts. The fence-sections can, however, 75 be formed by securing the rails together by battens G, of which there will be one near each end of the section and two on opposite sides at its middle. In this case the ends of the rails interlock, as before, and the weight 80 of the rails causes the posts to bind firmly upon them.

It will be seen from the above description that I construct a hinged or flexible sill, to which the posts B are rigidly secured, and that 85 by this construction I make the posts serve as clamps for binding the panels together.

Having thus described my invention, what I claim is—

1. The clamping-posts B B, secured to sills 90 A A, which are pivoted together, in combination with the braces c c, adapted to operate substantially in the manner and for the purposes described.

2. The combination, with the sills A, of the 95 posts B, secured thereto, the pivotal connection between the sills, and the inclined braces, notched at their ends and fitted to the posts and the sills in the manner specified.

In testimony that I claim the foregoing as 100 my own I affix my signature in presence of two witnesses.

EDWIN LORENZO DUNHAM.
